WITNESS:

UNITED STATES PATENT OFFICE.

LESLIE E. PURKEY, OF POCATELLO, IDAHO.

LEVELING DEVICE.

Application filed October 8, 1923. Serial No. 667,351.

This invention relates to leveling devices and has for an object the provision of a device which may be adapted for grading, leveling, etc., the device indicating the inclination of a surface or the rise and fall between any two points, the distance between which may vary.

Another object of the invention is the provision of a device which may be adapted for use as an ordinary spirit level, or for use as a surveyor's level between spaced points.

With the above and other objects in view, the invention further includes the following novel features and details of construction, to be hereinafter more fully described, illustrated in the accompanying drawings and pointed out in the appended claim.

In the drawings:—

Figure 1 is an elevation showing a pair of containers flexibly connected to provide a leveling device constructed in accordance with the invention.

Figure 2 is a view of one of the containers and its support.

Figure 3 is a plan view of the same.

Figure 4 is a vertical sectional view taken through a container and supporting means therefor.

Referring to the drawings in detail wherein like characters of reference denote corresponding parts, the invention is shown as comprising a pair of containers designated generally at A and comprising a casing 10 which is open at each end and which is cut away as at 11 to provide a sight opening. Located within the casing is a transparent tube or sleeve 12 which is held in position within the casing by providing at one end a cap or closure 13, whose threaded neck 14 is removably positioned within one end of the casing 10. The opposite end of the sleeve 12 is closed by a plug or cap 15 which has interposed between it and the end of the sleeve a gasket 16 to prevent leakage.

The cap 13 is provided with a centrally arranged opening which is normally closed by a plug 17, the latter being held in closed position by means of a spring arm 18 whose

tension is adjustable by means of a set screw 19.

The housing or casing 12 is secured upon a stand which includes spaced plates 20 and 21, connected by posts 22, the last mentioned plate being provided with spaced openings 23 for the passage of fastening devices, whereby it may be removably attached to a support, if desired.

As stated, the containers A are arranged in pairs and are connected by means of a flexible tube 26, controlled by a valve 26^a. Each of the transparent sleeves 12 is graduated as shown at 27, the graduations starting at zero at the mid portion of the tube and running in opposite directions.

The transparent sleeves 12 are adapted to contain a suitable non-freezing liquid and when in use, the difference between levels may be read upon the graduations 27. While the flexible tube 26 is shown as extending from the bottom of the containers, it is obvious that it may be extended from the side at the bottom.

Pressure is relieved within sleeves 12 by pressing upon the plugs 17, which are held seated by screws 19 and springs 18, whereupon liquid within the said sleeves will seek its proper level.

The invention is susceptible of various changes in its form, proportions and minor details of construction and the right is herein reserved to make such changes as properly fall within the scope of the appended claim.

Having described the invention what is claimed is:—

A leveling instrument of the character described comprising a pair of spaced and communicating graduated liquid containers, each container embodying a cylindrical casing cut away upon one side to provide a sight opening, a translucent tubular member positioned within each of the casings and providing graduations visible through the sight openings and registering with the graduations thereon, removable closures arranged upon the opposite ends of the casings for holding the tubular members there-

in, relief plugs having their shanks extending upwardly from the uppermost closures and having their heads positioned within seats provided on the underside of the respective upper closures, substantially offset and apertured spring fingers arranged upon the upper side of corresponding closures and receiving the shanks of the plugs within

the apertured portions thereof, and knobs threadedly secured to the shanks of the plugs for regulating the tension of the spring fingers in the seating of the plugs substantially as set forth.

In testimony whereof I affix my signature.

LESLIE E. PURKEY.
